UNITED STATES PATENT OFFICE.

MICHAEL L. MURPHY, OF CORAOPOLIS, PENNSYLVANIA.

GLASS-FURNACE.

SPECIFICATION forming part of Letters Patent No. 476,672, dated June 7, 1892.

Application filed September 16, 1891. Serial No. 405,910. (No model.)

To all whom it may concern:

Be it known that I, MICHAEL L. MURPHY, a citizen of the United States, residing at Coraopolis, in the county of Allegheny and State 5 of Pennsylvania, have invented certain new and useful Improvements in Glass-Furnaces; and I do hereby declare the following to be a full, clear, and exact description of the invention, such as will enable others skilled in the 10 art to which it pertains to make and use the same, reference being had to the accompanying drawings, which form a part of this specification, in which—

Figure 1 is a vertical longitudinal section 15 on line $y-y$ of Fig. 2. Fig. 2 is a horizontal section on line $x-x$ of Fig. 1. Fig. 3 is the same on line $z-z$ of Fig. 1.

My invention relates to that class of furnaces specially adapted to smelting glass; and 20 it consists in the novel construction and arrangement of parts hereinafter specifically described, reference being had to the accompanying drawings, forming part hereof.

Referring to said drawings, A A are producers, arranged on either side the well or eye B, which rests and is supported upon the eye-plate b and is provided with teaze-holes c c, through which coal, when it is necessary or desirable to use the same, may be charged 30 into said eye. Grate-bars to admit of this may be supported upon the bars d, four in number, which extend across the bottom of said eye, one at either side and two at the center. Said producers are connected and com-

35 municate with said well or eye by means of the arched channels or passage-ways C, which enter said eye tangentially at opposite sides thereof, the side x of said tangential channels, respectively, that opens into the eye almost

40 on a line with the center of the same and the walls of the eye on a line therewith, respectively, some distance above and below the plane of said channels project into said eye, as shown in Figs. 1 and 2, whereby the gases

45 are given a spiral or swirling motion in ascending said eye. For the purpose of giving additional velocity to the gas in its passage from said producers to said eye, I admit steam through pipes e, which are located beneath 50 the rear ends of the grate-bars g g of said producers, respectively, and serve as the rear

bearing-bars for the same. Said pipes are provided with a number of perforations through the rear of the same, (indicated by the arrow x'), whereby moisture, if any there may be, is 55 permitted to drip into the cinder-box beneath, and the steam, superheated and dry, is enabled to ascend through said grate-bars and mingle with the gases generated in said producers, increasing the velocity of the same toward the eye and adding largely to the combustion of the same therein. The side walls of said producers, respectively, are provided with air-ports h h, opening from the front near the bottom of the same, for the admission of 60 air to the horizontal flues k k k k, arranged one above the other in said side walls and communicating at the rear and front, alternately, as shown in Fig. 1, the upper of said flues respectively opening into the hot-air 65 chamber m, which entirely surrounds said eye or well. n n are ports in the side of said eye at the bottom of the same and entering said chamber m. Near the top of said eye and communicating with said chamber are a number of ports p p p p for admission of heated 70 air into said eye. r r are doors in the front of said producers, respectively, through which the same may be charged. s and s are dampers for the purpose of closing the channels 75 between the producers and the eye of said furnace, whereby one or both of said producers may be shut off, if necessary or desirable, and the furnace be operated by one producer and the well or by the well alone. 80

85 Some of the advantages of my furnace (aside from attaining intense combustion economically) are that I am enabled to place the producers quite a distance from the well or eye of the furnace, and from the peculiar construction of the gas-discharging channels connecting the said producers and well attain very great velocity in the passage of the gas from said producers to the point of combustion in the eye or well. The hot-air chamber 90 surrounding the eye or well not only enables me to utilize all the waste heat from the walls of the same to raise the temperature of the air in said chamber, but interposing, as it does, between the eye and producers protects the 95 latter from the excessive heat of the former. The construction of the air-flues in the side 100

walls of the producers also enables me to utilize the heat of the same to raise the temperature of the air before its admission to the chamber surrounding the eye of said furnace.

5 Having described my invention, what I claim, and desire to secure by Letters Patent, is—

1. In a glass-melting furnace, substantially as described, the combination of a deep well 10 or eye, an air-chamber surrounding the same, and one or more producers arranged at the side or sides of said eye or well and connected therewith by a passage opening tangentially therein, said producers having air-flues located 15 in the side walls of the same and communicating with said air-chamber, substantially as and for the purpose set forth.

2. In a glass-melting furnace, substantially as described, the combination of a deep well

or eye, an air-chamber surrounding the same 20 and communicating therewith, one or more producers arranged at the side or sides of said eye and connected therewith by a channel or passage opening tangentially therein, said producers having air-flues located in the side 25 walls of the same and communicating with said air-chamber, and a perforated pipe located beneath said producers, respectively, for the admission of steam thereto, substantially as set forth.

30 In testimony that I claim the foregoing I hereunto affix my signature this 3d day of September, A. D. 1891.

MICHAEL L. MURPHY. [L. S.]

In presence of—

CHARLES LARGE,
JNO. H. RONEY.
